Application March 12, 1953, Serial No. 341,966

10 Claims. (Cl. 198—185)

This invention relates to a conveyor and more particularly to a conveyor which is adapted for use in a sorting operation.

Many present day businesses involve a sorting operation of one kind or another, in which a large quantity of objects are sorted or graded on the basis of one or more of their characteristics. For example, vegetables and fruits must be sorted from undesired objects such as clouds of dirt, stones, rocks and the like and are generally graded on the basis of size. Many manufacturing procedures involve a sorting operation based on one or more of the characteristics of the manufactured object. Generally, these sorting and grading operations are carried on by moving the objects past one or more sorting or grading points on a conveyor of some sort. Means are provided for removing selected objects from the conveyor either at the sorting point or at some other predetermined point. These means may take various forms, for example, a stream of air may be used to blow the selected objects from the conveyor or an arm may be employed to push the selected objects from the conveyor. This invention is concerned with a new conveyor structure made up of a plurality of members which may be released to drop the selected objects from the conveyor.

One feature of this conveyor is that it includes a moving element, a plurality of releasable members carried by the moving element and adapted to support articles, means for releasing only selected members to drop the articles carried thereby and means for returning the released members to their original position. Another feature is that the releasable members are fingers pivotally carried on the moving element and each having an elongated portion normally extending substantially horizontally and a base portion having a slot therein adapted to receive the pivot on the moving element and in which the releasing means effects translatory movement of the slotted portion relative to the pivot whereby the finger member rotates about the pivot and hangs freely. A further feature is that a bracket is attached to the moving element and carries the pivot which supports the finger members. And another feature is that the fingers are normally carried on the pivot with the elongated portion extending substantially horizontally and with the base portion bearing against the bracket. And a further feature is that an inclined rail is provided beneath the tips of the fingers at the point of release for controlling the rate of fall of the released fingers.

Further features and advantages of our invention will be apparent from the specification and drawings, in which:

Figure 1 is a side elevational view of a conveyor embodying our invention;

Figure 2 is a top plan view of the conveyor of Figure 1;

Figure 3 is a fragmentary top plan view of a portion of the conveyor;

Figure 4 is a sectional view taken along the line 4—4 of Figure 3; and

Figure 5 is a sectional view taken along the line 5—5 of Figure 3.

In the particular embodiment illustrated, and referring now to Figures 1 and 2, the conveyor is supported on a framework made up of base members 10 and 11 and uprights 12, 13, 14 and 15 which are disposed in pairs at either end of the base members. The upper ends of the uprights are braced by longitudinal members 16 and

2

17 which extend between uprights 12 and 13, and 14 and 15, respectively, and which are preferably L-shaped. An axle 18 is journaled on uprights 12 and 14 and carries a pair of spaced, toothed wheels 19 and 20, keyed thereto. An axle 23 journaled on uprights 13 and 15 carries a second pair of spaced, toothed wheels 24 and 25.

A pair of endless link chains 26 and 27 are supported by corresponding wheels at either end of the structure; wheels 19 and 24 supporting chain 26 and wheels 20 and 25 supporting chain 27. The chains 26 and 27 form the basis of the conveyor and preferably lie along the horizontal portion 16a and 17a, respectively, of the longitudinal members 16 and 17.

A drive shaft 28 is journaled on the upright 14 and carries a spur gear 29 which engages the gear 30 mounted on wheel 20. A source of rotary power (not shown) turns the drive shaft 28 and through the gears 29 and 30 drives the wheels 19 and 20. This motion is transmitted to the link chains 26 and 27 which move in a clockwise path as seen in Figure 1.

The link chains 26 and 27 are of any suitable type and are preferably made up of a series of pivotally interconnected plates 33. Secured to alternate plates 25 are U-shaped brackets 34, held in place by means of screws 35 (Figure 3). These brackets are mounted on facing edges of the two chains 26 and 27 and each one extends substantially the length of an individual side plate 33. Carried between the extending arms 34a of the U-shaped brackets 34 is a pivot member 36. Carried on this pivot member are two releasable finger members 37 separated by a spacer 38.

As may best be seen in Figures 4 and 5, fingers 37 have an elongated portion 37a and an enlarged base portion 37b substantially at right angles thereto. The base portion 37b has a slot 39 therein, adapted to receive the pivot 36. When the fingers are in normal conveyor position, Figure 5, the pivot 36 is at the top 39a of the slot 39 and the lower portion 37c of the base 37b of the finger bears against the bracket 34, maintaining the elongated portion 37a of the finger in an outwardly disposed or substantially horizontal attitude. The distance from the pivot 36 to the bracket 34 must be less than the distance from the top 39a of the slot 39 to the bottom 37d of the base portion of the finger so that the base portion will contact the bracket and maintain the finger in the desired position. The elongated portions of the fingers carried by the two link chains 26 and 27 extend inwardly from the chains, toward each other and form a substantially complete surface for supporting the articles to be carried by the conveyor. Preferably, the dimensions of the bracket 34, pivot 36, base portion 37b and slot 39 are so related that the elongated portions 37a of the fingers incline slightly downwardly toward the center of the conveyor to facilitate centering of the objects carried thereon.

The tripping operation by means of which certain of the articles carried by the conveyor may be sorted from the other articles carried thereby is accomplished in the following manner. As may be seen in Figures 1 and 2, a tripping wheel 42 is pivotally carried at one end of a centrally mounted lever arm 43 carried on the longitudinal member 17. The tripping wheel is so mounted that it is directly beneath the base portion 37b of the fingers 37 carried by chain 27 as the conveyor moves along. A similar tripping wheel 44 and lever arm 45 are mounted under the fingers carried by the chain 26, the other side of the conveyor.

In order to trip or release the selected fingers, means are provided which cause the tripping wheels 42 and 44 to move upwardly, effecting translatory upward movement of the slotted portion 39 about the pivot 36, as shown in broken lines in Figure 4. This allows the entire finger to turn about the pivot 36 and hang downwardly, as shown in full lines in Figure 4. The distance from the pivot 36 to the bracket 34 must be greater than the thickness of the lower end of the base 37b of the finger, that is the distance from the lower end 39b of the slot to the bottom 37d of the base, in order that the finger will pivot properly and hang downwardly. Any articles carried by

the selected finger at the time they are tripped or released may fall into a receptacle of any suitable sort placed beneath the conveyor or onto another conveyor or the like (not shown).

In the embodiment of the invention shown in the drawings, the lever arm 43 has the core 46a of a solenoid 46 pivotally secured to the end thereof opposite the end at which the tripping wheel 42 is attached. The solenoid 46 is mounted on a bracket 47 suspended from the longitudinal member 17. When the solenoid 46 is energized, the core thereof is pulled downwardly causing the tripping wheel to be moved upwardly, effecting upward translatory movement of the base portions 37b of the fingers 37 which pass over the wheel during the time it is raised; when the solenoid is deenergized, the tripping wheel returns to its original position. The solenoid coil 45 may be energized from a source of electrical power (not shown) by the manual operation of a switch or by any suitable sorting control device. See for example, copending Burbidge and Hetland application, Serial No. 333,096, filed January 26, 1953, which discloses an electronic sorting control circuit. A similar solenoid control arrangement may be provided for the other tripping wheel 44.

A pair of inclined rails 47 and 48 may be placed under the tips of the fingers carried by each of the chains 26 and 27 at the release point. These rails are inclined downwardly in the direction of travel of the conveyor and control the rate of fall of the tips of the released fingers. Their use is particularly advantageous to prevent a sudden drop of easily bruised articles such as fresh vegetables, fruit and the like.

Although this invention has been described in connection with a conveyor having only a single release point, it is to be understood that a plurality of release points may be provided along the length of the conveyor. For example, a sorting apparatus with a plurality of release points would be used where articles were being graded into various classifications on the basis of size or color or the like; the articles of one standard would be released at the first point, those of a second standard at a second point and so on.

In operation the articles to be sorted would be fed to the conveyor from suitable means such as a gravity feed hopper (not shown) at the left end thereof as viewed in Figures 1 and 2. The articles would be moved along by the conveyor to the right in Figures 1 and 2 past the selection point where the selected articles are dropped from the conveyor while those articles which are not selected would move on and fall from the end of the conveyor at the far right.

The chains 26 and 27 pass over the wheels 24 and 25 and then back under the main run of the conveyor to the wheels 19 and 20. As the chains 26 and 27 pass around the wheels 19 and 20 it is necessary to insure that the fingers 37 will return to their normal outwardly extending position, so as to form the surface of the conveyor. In order to accomplish this, a pair of curved guide rails 50 and 51 are provided. These guide rails are mounted on the base members 11 and have an upwardly extending portion 50a and 51a respectively which extends upwardly to a point slightly above the lower edge of the wheels 19 and 20. A second portion 50b and 51b of the guide members extends gradually inwardly toward the center of the conveyor in a generally vertical plane to a point opposite the horizontal axis of the wheels 19 and 20. A third portion 50c and 51c extends on inwardly toward the center of the conveyor and generally follows the curvature of the wheels 19 and 20; while a fourth portion 50d and 51d extends along the top of the tips of the fingers and follows the curvature of the wheels 19 and 20. The guide rails 50 and 51 engage the fingers 37 as they pass around the wheels 19 and 20 and cause them to return to their desired conveyor position. A pair of discs 52 and 53 are mounted on the axle 18 and are of such a diameter that the tips of the fingers 37 rest on the peripheral edges of the discs as they are returned to their normal conveyor position. This prevents the fingers from hanging downwardly as they return to the main run of the conveyor and insures that the base 37b of the fingers will assume its proper relationship with the pivot 36 and bracket 34.

In some instances, it will be desirable to cause all of the fingers 37 to hang downwardly during the return run of the conveyor. Fingers which have not been released may do this automatically, while those which have been re-

leased will not do so, but rather will engage the bracket and extend outwardly during the return run. During many sorting operations weeds, vines and the like may be mixed in with the articles being sorted and it is desirable to cause

them to be dropped from the conveyor during the return run. In order that all the fingers 37 will hang downwardly during the return run, a roller 54 is provided along the lower portion of the periphery of wheel 25. This roller is mounted on a bracket 55 extending upwardly from the base member 11 and is so positioned that it bears against the top of the base portion 37b of the fingers and causes them to move so that the pivot 36 is at the top of the slot 39. Thus, the fingers are free to hang downwardly during the return run. A similar roller may be provided adjacent the wheel 24.

While we have shown and described certain embodiments of our invention, it is to be understood that it is capable of many modifications. Changes, therefore, in the construction and arrangement may be made without departing from the spirit and scope of the invention as disclosed in the appended claims.

We claim:

1. A conveyor of the character described, comprising: a moving element; means for driving said moving element; mounting means including a pivot on said moving element; a plurality of releasable fingers pivotally carried by said mounting means, each finger having an elongated portion normally extending substantially horizontally and a base portion having a slot therein adapted to receive said pivot; and means for releasing only selected fingers by effecting translatory movement of said slotted portion relative to said pivot whereby they rotate about said pivot and hang freely.

2. A conveyor of the character described, comprising: an endless moving element; means for driving said moving element; mounting means including a pivot on said moving element; a plurality of releasable fingers pivotally carried by said mounting means, each finger having an elongated portion normally extending substantially horizontally and a base portion having a slot therein adapted to receive said pivot; means for releasing only selected fingers by effecting translatory movement of said slotted portion relative to said pivot whereby they rotate about said pivot and hang freely; and guide means for returning said released members to their original position.

3. A conveyor of the character described, comprising: an endless link chain; means for driving said chain; bracket means attached to the links of said chain; pivot means carried by said brackets, parallel to and alongside each link; a plurality of spaced releasable finger members pivotally mounted on said brackets, said finger members having an elongated portion normally extending substantially horizontally from said links and a base portion having a slot therein to receive said pivot means, said base portion bearing against said bracket; camming means operable to move the base portion of selected finger members upwardly whereby said selected finger members rotate about said pivot and hang freely; and guide means for returning said selected finger member to their normal position.

4. A conveyor of the character described, comprising: a pair of spaced parallel endless moving elements; means for driving said moving elements; mounting means including a pivot on the facing edges of both of said moving elements; and a plurality of releasable fingers carried by said mounting means, each finger having an elongated portion normally extending substantially horizontally and a base portion having a slot therein adapted to receive said pivot; and means for releasing only selected fingers on both of said moving elements by effecting translatory movement of said slotted portion relative to said pivot whereby they rotate about said pivot and hang freely.

5. Apparatus of the character described in claim 4 in which the tips of the elongated portions of the fingers carried by one of the moving elements are adjacent the tips of the fingers carried by the other moving element and said tips are below the level of the top of said base portion.

6. A conveyor of the character described, comprising: a moving element; means for driving said moving element; mounting means including a pivot on said moving element; a plurality of releasable fingers pivotally carried by said mounting means, each finger having an elongated portion normally extending outwardly and a base portion having a slot therein adapted to receive said pivot; means for

releasing only selected fingers by effecting translatory movement of said slotted portion relative to said pivot whereby they rotate about said pivot and hang freely; and means for controlling the rate of fall of said released fingers.

7. A conveyor of the character described, comprising: an endless moving element; means for driving said moving element; mounting means including a pivot on said element; a plurality of releasable fingers pivotally carried by said mounting means, each finger having an elongated portion normally extending outwardly and a base portion having a slot therein adapted to receive said pivot; means for releasing only selected fingers whereby they rotate about said pivot and hang freely and an inclined rail under the tips of the fingers at the point of release to control the rate of fall of said released fingers.

8. A conveyor of the character described, comprising: an endless link chain; means for driving said chain; bracket means attached to the links of said chain; pivot means carried by said brackets, parallel to and alongside each link; a plurality of spaced releasable finger members pivotally mounted on said brackets, said finger members having an elongated portion normally extending substantially horizontally from said links and a base portion having a slot therein to receive said pivot means, said base portion bearing against said bracket; camming means operable to move the base portion of selected finger members upwardly whereby said selected finger members rotate about said pivot and hang freely; and an inclined rail under the tips of said fingers at the point of release for controlling the rate of fall of said released fingers.

9. In an endless conveyor, releasable means of the character described, comprising: mounting means adapted to be attached to said conveyor and including a pivot; at least one releasable finger pivotally carried by said mounting means, said finger having an elongated portion normally extending substantially horizontally and a base portion having a slot therein adapted to receive said pivot; and release means for effecting translatory movement of said slotted portion relative to said pivot whereby said finger rotates about said pivot and hangs freely.

10. In an endless conveyor, releasable means of the character described, comprising: a bracket adapted to be attached to said conveyor; a pivot carried by said bracket; at least one releasable finger member pivotally mounted on said bracket, said member having an elongated portion normally extending substantially horizontally and a base portion having a slot therein transverse of said elongated portion and adapted to receive said pivot, said base portion bearing against said bracket; and release means for camming said base portion upwardly whereby said member turns about said pivot and said elongated portion hangs freely.
